UNITED STATES PATENT OFFICE.

FREDERIC FULLER, OF PROVIDENCE, RHODE ISLAND.

IMPROVEMENT IN APPARATUS FOR MOLDING PIPE.

Specification forming part of Letters Patent No. 101,853, dated April 12, 1870.

To all whom it may concern:

Be it known that I, FREDERIC FULLER, of the city and county of Providence, and State of Rhode Island, have invented a new and Improved Apparatus for use in the Manufacture of Hollow Cast Pipes; and I do hereby declare that the following specification, taken in connection with the drawings making a part of the same, is a full, true, and exact description thereof.

My invention is intended to provide a convenient apparatus especially designed to be employed in the manufacture of the smaller sizes of cast-metal pipes.

It relates, first, to an improved molding apparatus; and, secondly, to an improved clamp for securing the molds in a stack when finished, and facilitating their handling.

The several figures illustrating the invention will be explained in the description.

A, Figures 2 and 3, represents a frame-work, which should be of the usual height of a molder's bench, and may be of any convenient length. It is made with an offset, *a a*, the higher portion being the molding-bench proper. The difference in height between the bench and that portion used as a flask-rest or temporary place of deposit for the mold when finished, as hereinafter explained, I prefer should be at least equal to the depth of the flask-frame B, Fig. 1. To the bench, at the edge of the offset, is hinged a match-plate, C, and so arranged that it can be laid flat upon the molding-bench, as seen at Fig. 2. The face of the match-plate, which will be uppermost when the plate is resting on the bench, is furnished with holding-clips *b*, whose shanks extend through the plate, and are provided with handles for working them. The object of these clips is to fasten the flask-frame B to the match-plate during the molding operation and until the mold is withdrawn from the pattern and placed face upward, as hereinafter to be explained.

D is the pattern for the pipe to be molded. It is furnished with extensions for core-prints *c c*, and is to be properly adjusted in position across the bench, resting in curved notches cut in the side rails of the frame. Supposing the pattern to have been placed on the bench, the match-plate C, constructed with reference

to the pattern, as will be understood by all pattern-makers, is turned down upon the bench, as in Fig. 2, forming the temporary bottom plate for the flask B, which latter is placed over the pattern and fastened to the match-plate by the holding-clips *b*. It is to be understood that in this position the plane of the upper face of the match-plate will coincide with a plane passing through the longitudinal axis of the pattern and parallel with the plane of the bench.

The molder now fills the flask with sand and rams it properly to take the impression of the pattern. This completed, the match-plate, with the flask and mold, should be carefully turned over and rested upon the lower platform of the frame. The mold will then be withdrawn from the pattern, which will be left in its proper bearings on the bench. The clips can now be turned so as to disconnect the match-plate from the flask, when the match-plate can be turned back again upon the bench, Fig. 3, preparatory to receiving a fresh flask for the repetition of the molding operation.

The mold E is left face upward upon the frame, from which, after being suitably prepared, it is taken to the oven for baking.

It is evident that with the apparatus described no skilled labor is required. Any intelligent laborer is capable of doing the work as well as the best molder.

After the requisite number of flask-frames have been filled with molds they are to be matched in sets of two, a core having been first laid in the mold with its ends resting in the prints made for it. Two or more sets of flasks may be stacked one above another, as seen at Fig. 4, and supplied with top and bottom plates F F'. These plates are then strained toward each other by means of straining rods or bars G, and thus securely confine the flasks contained between them. The construction of the improved clamp which I use is shown at Fig. 4. Mortises are cut near the edge of the lower plate, into which the ends of the bars G, made with a lip, *d*, for the purpose, are hooked.

Double ear-pieces, the spaces between which correspond in number and location with the mortises in the lower plate, project from the edge of the upper plate, and the bars G having been entered between such ear-pieces, keys

e are driven through key-seats *f* made in the upper ends of the bars, whereby the top and bottom plates are made to compress the molds.

For convenience in handling the molds in the operation of setting them upright in a pit preparatory to pouring the metal to make the pipe, one pair of the clamp-bars should be furnished with trunnions or holding-ears *g*, by which the trammels attached to fall of the foundry-crane can raise the stack of flasks.

The whole apparatus above described possesses important advantages over any devices before to my knowledge employed in the manufacture to which it is adapted.

It has been the universal practice among foundrymen heretofore to mold the pipe without the use of a match-plate, to set the mold upright in the pit, and after drawing the pattern to insert the core in its place. While this mode of operation is perhaps necessary in the manufacture of the larger sizes of pipes, it is inconvenient and unnecessarily expensive in the manufacture of smaller sizes. The cores are liable to be bent in handling, and consequently

the pipe made thin upon one side. The process is expensive, and requires the labor of the best skilled workmen.

My apparatus economizes the manufacture, both in the time necessary to be expended and in the grade of educated labor required to do the work.

What I claim as my invention, and desire to secure by Letters Patent, is—

1. The improved apparatus for use in the manufacture of cast-metal pipes, which consists of the combined molder's bench and flask-rest *A*, the match-plate *C*, and flask *B*, in combination, substantially as described.

2. The improved clamp for molders' flasks consisting of the top and bottom plates *F'F* and the connecting-bars *G*, (one pair furnished with trunnions or holding-ears *g*), constructed and combined substantially as described.

FREDERIC FULLER.
